UNITED STATES PATENT OFFICE.

EVERTON B. POWELL, OF NEWARK, NEW JERSEY, ASSIGNOR OF ONE-HALF TO
FREDERICK N. WINDRIDGE, OF CHERRYDALE, VIRGINIA.

HAIR-CUTTING MACHINE.

1,421,350.

Specification of Letters Patent. Patented June 27, 1922.

Application filed August 14, 1920. Serial No. 403,492.

To all whom it may concern:

Be it known that I, EVERTON B. POWELL, a citizen of the United States, and resident of Newark, in the county of Essex and State 5 of New Jersey, have invented new and useful Improvements in Hair-Cutting Machines, of which the following is a description, reference being had to the accompanying drawings, which are a part of this specification.

The present invention relates to certain new and useful improvements in cutters and refers more particularly to what may be termed a hair cutting machine.

15 Heretofore, the machines of this character have been constructed and designed to be operated by an electrical motor distant from the machine and connected therewith by a flexible shaft. This construction has 20 always been open to numerous objections in that flexible shafts produce considerable friction and are cumbersome and the machinery for transmitting the motion of the flexible shaft to the cutting blade proper generally 25 imparts a jarring and vibratory sensation to the operator.

Hence with the above and other objections in mind this invention has for one of its objects to provide a hair cutting machine 30 in which the driving or operating mechanism is self-contained within the handle thereof to thus eliminate the flexible shaft.

Another object of this invention is to provide a machine of the class described which 35 is electrically operated and provided with switch means within the electrical circuit so constructed that the circuit will be closed when the machine is held by the operator in the normal position of use, and which circuit 40 will be automatically opened when the machine is out of the operator's hands to prevent a careless operator from leaving the machine running when he places the same upon a support.

45 A further object of this invention is to provide a machine of the class described, having solenoids contained within the handle thereof and provided with an armature in connection with the cutting blade for operating the same.

A further object of this invention is to provide a machine of the class described having means within the electrical circuit 50 operable to automatically reverse the flow 55 of current from one solenoid to the other

in rapid succession whereby the armature will be rapidly reciprocated to operate the cutting blade connected therewith.

A still further object of the present invention is to provide a machine of the class 60 described so constructed that the same may be produced at the lowest possible cost and will be positive and efficient in operation and having all the parts readily accessible for the purpose of replacement or repairs. 65

A still further object of this invention is to provide means operable automatically upon the release of the hand operated switch control lever for moving the armature to a position off center to insure the positive operation of the device when the circuit is closed. 70

With the above and other objects in view which will appear as the description proceeds, my invention resides in the novel construction, combination and arrangement of parts substantially as hereinafter described and more particularly defined by the appended claims, it being understood that such changes in the precise embodiment of the 80 hereindisclosed invention may be made as come within the scope of the claims. 75

In the accompanying drawing, I have illustrated one complete example of the physical embodiment of my invention constructed according to the best mode I have so far devised for the practical application of the principles thereof, and in which: 85

Figure 1 is a view part in section and part in elevation taken longitudinally through 90 the machine on the plane indicated by the line 1-1 of Figure 2;

Figure 2 is a top view of the machine with the cover or upper portion of the handle thereof removed; 95

Figure 3 is a transverse sectional view taken through Figure 1 on the line 3-3;

Figure 4 is a perspective view of the block and contacts carried thereby forming part of the make and break system of my machine; and 100

Figure 5 is a diagrammatic view of the electrical circuit employed for the operation of my machine.

Referring now more particularly to the 105 accompanying drawing in which like numerals designate like parts throughout the several views;

Numeral 1 designates the cover or top portion of the case or handle of the machine. 110

which is removably secured to the lower portion 2 of the handle by screws or other fastenings 3 and 4 and bolt 5. The forward end of the portion 2 of the machine handle is directed downwardly as at 2' and has rigidly secured thereto a fixed cutting blade 6, the blade 6 being held in place by the bolt 5 which passes therethrough and by guide pins 7 carried by the front projection 7' of the neck 2'.

Slidably mounted on the blade 6 and co-operating therewith is a movable cutting blade 8 having guide slots 9 therein through which the guide pins 7 pass and a central recess or notch 10 in which the forward end of an operating arm, to be later described, is pivotally engaged. The guide pins 7 pass through the slots 9 and tend to retain the blade 8 in proper alignment with the blade 6 and at the same time permit the limited reciprocation thereof.

The cover 1 of the handle is provided with spaced downwardly extending transverse projections 11, 12 and 13 between which are 25 movably secured two axially aligned solenoids 14 and 15. The solenoids are made of any desired shape, but preferably oblong cross section and have a central slot or bore extending through the iron cores 30 thereof which act as guides for a soft iron plunger or armature 17.

Mounted on one end of the armature or plunger 17 is a plate 18 of non-magnetic metal such as copper, brass, bronze or the 35 like having a cam slot 19 therein. Medially pivotally mounted on the bolt 5 is a driving arm 20 having the forward end thereof rounded and engaging within the recess 10 of the movable cutting blade and having 40 the rear end thereof positioned under the cam plate 18 and connected thereto by a cam roller or pin 21 engaged within the cam slot 19.

Secured to the under side of the arm 20, 45 directly beneath the roller 21, is a non-conducting block 22 having a recess 23' communicating with the bottom face thereof and in which is mounted one end of a contact member 24. The contact 24 is at all 50 times urged outwardly from the recess 23 by an extensile spring 25 within the recess and confined between the contact 24 and the inner end of the recess. Rigidly secured to the bottom portion 2 in line with the 55 block 22, is a second block 26 of non-conducting material and provided with contact faces or members 27, 28 and 29, more clearly shown in Figure 4. The block 26 is recessed where the contacts 27, 28 and 29 are 60 secured thereto so that the whole will present a smooth surface, and said contacts have downwardly extending lugs provided with screws or other means for forming terminals to which the electric wires, hereinafter described, may be readily secured.

The block 22 is so positioned that its contact member 24 will bear upon the top face of block 26 and be free to slide thereon as arm 20 is moved under the influence of the solenoid and cam slot 19 and roller 21, to 70 alternately bridge the gap between contacts 27 and 29, and 28 and 29.

Rigidly secured to the portion 2 near the rear end thereof is a third block 30 of non-conducting material having spring clips 31 75 and 32 secured thereto and forming with the knife or bridge member 33, a switch mechanism. The member 33 is fixed to the inner end of a plunger rod 34 so that the movement of the plunger rod toward the 80 clips 31 and 32 will engage the bridge member therewith to thus close the circuit. The plunger rod 34 is slidably mounted within a boss or bearing 35 carried by the handle portion 2 and is at all times normally urged 85 outwardly by an extensile spring 36 confined between the inner end of the rod and the adjacent portion of the casing wall 2. The spring 36 at all times normally urges the rod 34 outwardly of the casing or lower 90 portion 2 so that after the rod has been depressed by a control lever 37 the same will be immediately moved upon the release of said lever to disengage the knife member 33 from the contacts 31 and 32 to open the 95 circuit and thus render the machine inoperative.

Members 1 and 2 of the handle have registering recess portions 38 and 39 to provide bearing surfaces for the lever 37 which is 100 pivotally held in position by the screw 4. The portion of the lever 37 adjacent its pivot has a stop lug 40 which is engageable with the portion of the handle adjacent the recesses 38 and 39 to limit the movement of 105 the rear part of the lever away from the handle and consequently retard the outward travel of the plunger 34 upon the action of its spring 36.

The portion 2 of the handle has a recess 110 formed therein near the rear end thereof which is provided with a hard rubber or other non-conducting bushing 42 to prevent wires 43 and 44 which pass therethrough into the handle from becoming short circuited on the case. The wires 43 and 44 lead from any desired source of supply S and wire 43 is connected directly with the solenoids 14 and 15. Wire 44 is attached to the clip 31, and clip 32 is connected to contact 120 member 29 by a wire 45, while members 28 and 27 are connected respectively to solenoids 14 and 15 by wires 46 and 47.

The operation of my machine is briefly as follows:

When the handle of the machine is gripped, lever 37 is pressed against the handle, moving the plunger 34 inwardly against its spring 36 and engaging the bridge member 33 with the clips 31 and 32 closing the 130

circuit allowing current to pass to the center contact member 29. Contact 24 carried by the driving arm 20 will always be either bridging from members 29 to 27 or 28 to 29 5 so that the current will energize either solenoid 14 or 15. For example should solenoid 15 be energized, magnetic lines of force will be set up and tend to draw the plunger or armature 17 therein until equal lengths of 10 the plunger extend on each side of the solenoid.

As the plunger or armature 17 moves the cam slot 19 will act upon roller 21 and cause the arm to swing on its pivot, imparting to 15 the ends of said arm a side to side reciprocation. This movement of the inner end of the arm 20 will alternately cause contact member 25 to bridge contacts 27 and 29, and 20 28 and 29 to energize and deenergize the solenoids 14 and 15 in rapid succession. Immediately upon solenoid 15 being deenergized, solenoid 14 is energized and the lines of force set up in solenoid 14 will draw the plunger or armature 17 to a position so that 25 equal lengths thereof will project on each side of solenoid 14, when solenoid 15 will be again energized and solenoid 14 deenergized.

Cam slot 19 regulates the travel of the plunger or armature 17 so that it will at no 30 time reach the desired position and therefore always be in position to be acted upon by either solenoid 14 or 15. As the arm 20 is rapidly rocked on its pivot by the plunger or armature 17 through the medium of the 35 cam slot 19 and roller 21, the movable blade 8 will be rapidly reciprocated on the fixed blade 6 to cut or shear the particles which may be passed between the teeth 48 of said blades.

40 In order to insure against a possibility of the armature 17 being on dead center when the lever 37 is depressed, I provide means carried thereby for automatically moving the armature to a position off center immediately upon the release of said lever. To 45 accomplish this feature, a projection or lug 49 is formed on the inner end of the lever 37 and extends into the casing to engage the inner end of the armature when the lever 37 50 is released in the event that the armature should be at any point between dead center and its innermost position. When the lever is depressed against the machine handle, the lug 49 will be at the end of travel of the 55 armature and therefore will not interfere with the operation of the same. As the handle is released the lug 49 will force the armature back and thus prevent its stopping on dead center or in a position so that the 60 current will not flow when the handle 37 is again depressed.

From the foregoing description taken in connection with the accompanying drawing it will be at once apparent to those skilled 65 in the art to which an invention of this

character appertains that I provide a machine in which the operating mechanism is self-contained and which will form its functions in the most efficient manner and which is so designed that immediately upon the 70 hand of the operator being disengaged from the handle of the machine the electrical circuit will be opened and the machine rendered inoperative whereby damage thereto due to the carelessness of an operator neglecting to close the circuit of his own accord is prevented.

What I claim as my invention is:

1. In a device of the class described, a substantially hollow handle member, a movable member mounted at one end thereof, a pair of solenoids disposed within the hollow of the handle and longitudinally aligned therein, an armature slidable within the solenoids and capable of reciprocation longitudinally of the handle upon the simultaneous energization of one solenoid and deenergization of the other, and means connecting one end of said armature with said movable member whereby reciprocation of the armature will reciprocate the movable member at approximately right angles with respect to the armature.

2. In a device of the class described, a working member mounted for reciprocal movement, a solenoid, the axis of the solenoid being disposed at substantially right angles with respect to the plane of movement of said member, an armature slidably mounted in the solenoid, a connection between one end of the armature and said working member, whereby reciprocation of said armature will reciprocate said member at approximately right angles with respect to the armature, and means positioned adjacent the connection of the armature with the movable member for alternately closing and opening an electrical circuit in quick succession to alternately energize and deenergize the solenoid.

3. In a device of the class described, a working member mounted for reciprocal movement, a driving arm therefor having one end connected therewith, a solenoid, the axis of the solenoid being disposed at substantially right angles with respect to the plane of movement of said member, an armature mounted in the solenoid for reciprocal movement, a drive connection between one end of said armature and driving arm, an electrical circuit connected with the solenoid, and means within the circuit for rapidly alternately closing and opening the circuit to alternately energize and deenergize the solenoid whereby the armature will be rapidly reciprocated to operate said member through said driving arm.

4. In a device of the class described, a substantially hollow handle of substantially oval shape in transverse section, a movable

member carried by said handle, a pair of aligned solenoids longitudinally disposed in said handle, said solenoids being substantially oval shape in transverse section and 5 having longitudinally aligned elongated cores, a substantially flat armature slidably mounted in the cores of said solenoids, a connection between one end of said armature and a movable member, and means for 10 simultaneously alternately energizing one solenoid and deenergizing another in rapid succession to cause the armature to be rapidly reciprocated and operate said movable member by reason of its connection there- 15 with.

5. In a device of the class described, a substantially hollow handle, a reciprocally mounted member, a medially pivoted driving arm having its forward end connected 20 with said member, axially aligned solenoids secured within the handle, an armature for the solenoids, a connection between the armature and the rear end of the driving arm, and means for simultaneously alter- 25 nately energizing one solenoid and deener- gizing another in rapid succession to cause the armature to be rapidly reciprocated and rock said driving arm on its pivot to operate the said member.

30 6. In a device of the class described, a substantially hollow handle, a movable

member, a medially pivoted driving arm having its forward end connected with said member, axially aligned solenoids secured within the handle, an armature for the sole- 35 noids, a connection between the armature and the rear end of the driving arm and including a cam pin carried by the rear end of the driving arm and engaging in a cam slot carried by said armature, and means for simultaneously alternately energizing one solenoid and deenergizing another in quick succession to cause the armature to be rapidly reciprocated and rock 40 said driving arm on its pivot to operate said member. 45

7. In a device of the class described, a movable member means for operating said member including a solenoid, an armature cooperating therewith, a drive connection 50 between said member and armature and means for alternately energizing and de- energizing the solenoid, a lever adapted upon compression to close a circuit to operate the device, and means operable upon the 55 release of said lever to automatically move the armature from a position on dead center so that the same will be in place to be operated again.

In testimony whereof, I affix my signature. 60

EVERTON B. POWELL.
